UNITED STATES PATENT OFFICE.

CARL W. CHERRY, OF SAN FRANCISCO, CALIFORNIA.

MAGNETIC-LOCK-OPERATING DEVICE.

Application filed July 27, 1925. Serial No. 46,429.

This invention relates to magnetic locks in general and in particular to such magnetic locks as shown in the home savings bank, for which I have a copending patent application filed July 27, 1925, under Serial No. 46,428.

The principal object of the invention hereunder is to provide a special magnetic key for unlocking and locking home savings banks, such key to be in the custody of the banking institution issuing the small home savings banks so that the institution only will be enabled to open the bank to remove the accumulated savings therein.

10 The drawings hereto show the preferred construction of my magnetic lock operating device.

Figure 1 is a reduced size perspective view of the bank;

20 Figure 2 is a perspective view of the complete magnetic lock operating device with the bank dotted in position above it;

25 Figure 3 is an end view of the bank in position on the extended poles of the electromagnet with the concealed bolts dotted in operative relation to the poles, and in unlocked position; and

Figure 4 is an enlarged vertical section of the contact switch for completing the electrical circuit through the magnet windings.

30 The bank 1 is fully described in my copending application referred to, and therefore will only be sufficiently described herein to show the operativeness of the magnetic lock operating device of which this is a specification.

35 Figure 1 shows the bank as a bowl shaped receptacle 1 closed with a flat head or plate 2 having a hinged door 3 and a coin slot 4.

The door is preferably spring actuated so as to fly open when unlocked and is locked 40 when closed by sliding iron or steel bolts 5 thrown inward by springs 6 all concealed below the plate 2 permanently secured to the shell of the bowl, and is only unlocked by magnetic influence applied at the proper

45 points at opposite sides of the shell by the special electromagnet 7 shown in Figure 2.

This electromagnet has upwardly extending pole pieces 8 with inwardly confronting curved faces 9 against which the rim of the bank is placed when it is desired to unlock the same, a brass guard plate 10 extending from pole to pole braces them and functions as a stop to the flat end of the bank when the bank

is placed against the poles as shown in dotted lines in Figure 1, or full lines in Figure 3.

The bank being round, it must be revolved until the door 3 stands vertical with respect to the magnet 7 so as to bring the pole pieces directly in line with the ends of the bolts 5.

The shell of the bank and slidable mounting of the bolts is preferably of brass or other non-magnetic material so that the bolts will not have a tendency to be impeded through residual magnetism, and upon energizing the magnet the bolts are both drawn outwardly to the limits of travel, as indicated in Figure 3, thus unbolting the door and making it free to fly open.

To energize the magnet it is proposed to complete the electric circuit by pressing on a switch 11 with the rear end of the bank after revolving it to the correct position as mentioned.

70 This switch 11 is positioned so that it comes directly under the end of the bank as indicated in Figure 1 so that upon pressing downward on the rear end of the bank the switch will also be depressed to complete the circuit from the lead wires 12 and 12' delivering alternating current from the ordinary light 80 socket.

This switch and magnet are preferably mounted on a pair of insulating bases 13-13' with the wiring to the magnet concealed between them, and the dotted extensions 12 and 12' of the electric leads show the sub panel path of the current to the terminals 14-14' respectively of the magnet windings.

75 In Figure 4 the construction of the switch is seen to be a metal rod 15 vertically slidable in an insulating sleeve 16 secured to the blocks 17 in turn secured to the base 13, and adapted upon being depressed to contact a terminal 18 connected to the lead 12'' extending under the base from binding post 19 connected to lead 12'.

85 The switch is normally open, however, by a pair of wire springs 20 engaging a metal cross bar 21 secured to a flattened side of the rod 15 and active to urge the rod in an upward direction.

90 These springs form a path for the current from the rod 15 after same contacts the terminal 18 and lead the current to the screw 22 which secures the springs to the base, and 100 through which screw the current follows the

sub panel wire 12' to the magnet coil terminal 14'.

At the upper end of the switch rod 15 is an insulating sleeve 11 topped by a piece of 5 soft rubber 23 adapted for the bank shell 1 to rest upon when in the position shown in Figure 1.

It will thus be seen that with the wires 12—12' connected to the light socket, no energy flows through the magnet coils until the bank is placed in position and the rear end depressed to force down the switch which immediately energizes the magnet with the result of the powerful magnetic attraction in 15stantly pulling out both bolts against the tension of springs 6 to the position indicated in Figure 3, thus allowing the door to spring open, or when the bolts are thus withdrawn the door if open may be closed and the current broken to permit the bolts to snap inwardly and lock the door.

In contemplating the invention as above described, it will be evident that many changes in the form of switch and arrangement of wiring, etc., may be made without departing from the spirit of the invention;

and any such are intended to be embraced in the appended claims.

I claim:

1. A magnetic-lock operating device comprising a support for carrying a bank having a curved wall, a portion of said support to contact with said curved wall and to conform therewith, magnets carried by said support and being positioned so as to lie opposite 30magnetic bolts carried by a bank when the bank is disposed in place and means for energizing said magnets.

2. A magnetic-lock operating device comprising a support for carrying a bank having a curved wall, a portion of said support to contact with said curved wall and to conform therewith, magnets carried by said support and being positioned so as to lie opposite 35magnetic bolts carried by a bank when the bank is disposed in place and means for energizing said magnets, said means comprising a switch in electric connection with said magnets and with a source of current, said switch being actuated by the bank when the bank is disposed in position.

CARL W. CHERRY.
